UNITED STATES PATENT OFFICE.

JAMES L. BREESE, JR., OF CHICAGO, ILLINOIS, ASSIGNOR TO OIL DEVICES CORPORATION, OF CHICAGO, ILLINOIS, A CORPORATION OF ILLINOIS.

FLUID-FUEL-BURNING APPARATUS.

Application filed August 8, 1928. Serial No. 128,113.

My invention relates to an oil heater and particularly to a small oil heating unit adapted for domestic use or for garage heating although I do not wish to be limited to any specific use therefor. One object is the provision of such a unit, adapted to burn a liquid hydrocarbon fuel substantially without carbon deposit. Other objects will appear from time to time in the course of the specification.

I illustrate my invention more or less diagrammatically in the accompanying drawings, wherein—

Figure 1 is a vertical section; and

Figure 2 is an enlarged detailed section.

Like parts are indicated by like symbols throughout the specification and drawings.

A generally indicates a stove assembly having legs A¹, a bottom member A² and a downwardly depending rim A³.

B is an outer cylindrical section resting upon the bottom A². Supported upon its upper edge is the partition ring B¹ having the downwardly depending outer centering flange B² and the inner depending flange B³. B⁴ is a centering flange projecting from the upper face of the ring and adapted to position the radiator member C resting upon said ring. C¹ is a downwardly and outwardly inclined rim adapted to protect the upper edge of the drum B. C² is any suitable cover member for the radiator member C having for example the outwardly projecting flange C³ resting upon the upper edge of the cylinder and the downwardly depending centering flange C⁴. C⁵ is a protecting rim similar to the rim C¹. C⁶ is any suitable flue and C⁷ a pivoted transparent back-draft indicator adapted normally to rest against the abutment C⁸.

Within the drum B is the mixing drum D, the upper edge of which engages the bottom of the partition member B¹ and is centered by the flange B². It is herein shown as having a concave bottom D¹ in communication with the fuel inlet pipe D². D³ indicates a layer of sand in the bottom of the burner. The walls of the burner are provided with a plurality of air inlets D⁴. It will be noted that the lower edge of the drum D is free from such apertures and that the upper edge is provided with a plurality of larger and more closely spaced and upwardly and inwardly inclined apertures D⁵.

The bottom A² is provided with an air

inlet E adapted to be controlled by any suitable closure E¹, herein shown as a sliding member adapted to be actuated by the rod E² having the external handle member E³. E⁴ is a control rod extending from the closure member E¹ and adapted to actuate the fuel control valve E⁵ through the bell crank lever E⁶, the link E⁷ and the rocking lever E⁸.

It will be realized that whereas I have described and shown a practical and operative device that nevertheless many changes might be made in the size, shape, number and disposition of parts without departing from the spirit of my invention. I wish my drawings and description to be taken as in a broad sense illustrative or diagrammatic rather than as limiting me to the structure specifically described.

The use and operation of my invention are as follows:

I illustrate a stove unit comprising a lower drum and an upper drum, the combustion drum proper being centered within the lower drum, its open top communicating with the bottom of the upper drum, the lower drum being indicated as B, the upper drum as C, and the inner drum as D. The drum B houses and protects the combustion drum D and provides it with a controlled supply of air, the combustion drum being perforated throughout its area as below described. The supply of air may be controlled by the slide or damper E¹ in the air inlet E, such inlet being the sole passageway through which air is permitted to flow inwardly to support combustion.

The combustion drum D is herein shown as provided with a concave bottom in which may if desired be located a layer of sand or similar finely divided material. Any suitable means may be employed to deliver a supply of oil to this concave bottom and I illustrate the oil line D² controlled for example by the valve E⁵.

It is characteristic of my burner that the liquid fuel is vaporized by the radiant heat of combustion. In order to prevent the deposit of carbon and to promote the substantially complete combustion of the hydrocarbon employed, I prefer to employ a structure in which the hydrocarbon is first vaporized or gasified and then mixed with an initial air supply and hydroxylated, prior to complete combustion. In order to effect

- such hydroxylation, and to insure an air supply adequate therefor, but inadequate to support premature combustion, I employ the perforations D⁴ which are of such cross-section and number as to deliver into the mixing zone a supply of air sufficient for hydroxylation but insufficient to support complete combustion. The inflowing air is mechanically mixed with the upwardly rising vaporized or gasified hydrocarbon, and a chemical union takes place, the hydrocarbon being changed by the addition of oxygen into hydroxylated compounds in which the carbon molecules are associated with oxygen molecules, the deposit of free carbon being thereby prevented. In the normal operation of the burner the combustion, which takes place largely above the level of the partition member B¹, radiates the heat necessary for the vaporization and gasification of the liquid hydrocarbon exposed in the bottom of the drum D. The gasified fuel rises, and is hydroxylated by the admixture of the air through the apertures D⁴. Preferably, whether by controlling the inflow of air or the area and cross-section of the apertures D⁴, the air is so admitted as not to interfere with the normal upward rising of the gasified hydrocarbon and of the hydroxylated mixture formed therewith. It is extremely important that back-drafts and downward eddies be avoided and in the burner and mixing drum, as herein described and shown, experience shows that such back-drafts may be avoided by the proportioning and spacing of the apertures as herein shown. As the hydroxylated mixture rises, thus unimpeded by the cross circulation of air, it reaches the level of the apertures D⁵. These apertures direct, upwardly and inwardly, larger and stronger jets of air which combine with the hydroxylated hydrocarbon to form a combustible mixture. In the form herein shown the upwardly and inwardly inclined apertures direct converging jets of air to form a species of hood or cone into which the hydroxylated mixture rises. The combustion takes place as the said mixture receives the additional air necessary to support complete combustion and the heat of combustion is radiated from the walls of the cylinder C.
- As regards the specific proportioning of the apertures a considerable variation is allowable. However the total cross-sectional area of the upper row of apertures is preferably greater than the total cross-sectional area of all the rest of the apertures and it may be two or three times as great, or even more. It is essential both that a relatively small supply of air be provided for hydroxylation and also that the air be so supplied as not to impede the upward rise or flow of the gasified hydrocarbon and of the hydroxylated mixture. Any downward flow or eddy is highly damaging and destroys the conditions of combustion I wish to maintain, and interferes with the hydroxylation and permits a partial or complete combustion, prior to such hydroxylation, with a consequent deposit of carbon in the drum D and discharge of free carbon upwardly with the exhaust gases of combustion.
- The flap C⁷ is in practice an efficient means for preventing back-drafts down the flue and into the drum D which might otherwise interfere with the proper combustion. As the gate C⁷ is completely pivoted any substantial increase of pressure within the drum C opens the gate and is relieved by flow through the gate.
- I claim:
1. A mechanism for burning liquid fuels, which includes a chamber, means for admitting a liquid fuel to said chamber, means for directing a primary air supply into said chamber at a level above the level of said liquid fuel and for mixing said primary air supply with the vaporized liquid, and means for positively directing a secondary air supply upwardly and inwardly about the mixture thereby formed at a level above the level of admission of said primary air supply. 85
  2. A mechanism for burning liquid fuels, which includes a chamber, means for admitting a liquid fuel to said chamber, means for directing a primary air supply into said chamber at a level above the level of said liquid fuel and for mixing said primary air supply with the vaporized liquid, and means for positively directing a secondary air supply about the mixture thereby formed, at a level above the level of admission of said primary air supply in a plurality of upwardly and inwardly inclined jets. 90
  3. A mechanism for burning liquid fuels, which includes an apertured walled mixing chamber, means for delivering a liquid fuel to the bottom of said chamber, the apertures of said wall being divided into two zones, namely a primary air supply zone positioned at a level above the level of the liquid fuel, and consisting of a relatively large number of relatively small apertures, and means for delivering air through said apertures, the size and spacing of said apertures being adapted to effect a thorough mixture of the primary air supply so delivered with the vaporized or gasified fuel within the chamber, and a secondary supply zone above said primary supply zone, consisting of a relatively large number of somewhat larger apertures. 110
  4. A mechanism for burning liquid fuels, which includes an apertured walled mixing chamber, means for delivering a liquid fuel to the bottom of said chamber, the apertures of said wall being divided into two zones, 115

namely a primary air supply zone positioned at a level above the level of the liquid fuel, and consisting of a relatively large number of relatively small apertures, and

5 means for delivering air through said apertures, the size and spacing of said apertures being adapted to effect a thorough mixture of the primary air supply so delivered with the vaporized or gasified fuel within the 10 chamber, and a secondary supply zone above said primary supply zone, consisting of a relatively large number of somewhat larger apertures, said secondary apertures being formed to direct individual jets of air upwardly and inwardly about the mixture of 15 fuel and primary air.

5. A mechanism for burning liquid fuels, which includes a chamber and means for admitting a liquid fuel thereto, a cylindrical 20 wall for said chamber, provided with a plurality of primary air apertures positioned above the level of the liquid fuel, said wall being further provided, adjacent its upper edge, with a plurality of secondary air inlet 25 apertures, said secondary apertures being

shaped and positioned positively to direct upward and inward jets of air about the mixture formed of the primary air and the vaporized fuel.

6. A mechanism for burning liquid fuel, 30 which includes a chamber and means for admitting a liquid fuel thereto, a cylindrical wall for said chamber, provided with a plurality of primary air apertures positioned above the level of the liquid fuel, said wall 35 being further provided, adjacent its upper edge, with a plurality of secondary air inlet apertures, said secondary apertures being shaped and positioned positively to direct upward and inward jets of air about the 40 mixture formed of the primary air and the vaporized fuel, the total cross sectional area of the secondary air apertures substantially exceeding the total cross sectional area of 45 the primary air apertures.

Signed at Chicago county of Cook and State of Illinois, this 5th day of August, 1926.

JAMES L. BREESE, JR.
